US0D1078682S

(12) **United States Design Patent** (10) **Patent No.:** **US D1,078,682 S**
(45) **Date of Patent:** ** *Jun. 10, 2025

(54) **HEADPHONES**

(71) Applicant: **Apple Inc.**, Cupertino, CA (US)

(72) Inventors: **Jody Akana**, Los Altos Hills, CA (US); **Molly Anderson**, San Francisco, CA (US); **Bartley K. Andre**, Los Gatos, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Abidur Rahman Chowdhury**, San Francisco, CA (US); **Clara Geneviève Marine Courtaigne**, Palo Alto, CA (US); **Markus Diebel**, San Francisco, CA (US); **Jonathan Gomez Garcia**, San Francisco, CA (US); **M. Evans Hankey**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Sung-Ho Tan**, Vienna (AT); **Clement Tissandier**, San Francisco, CA (US); **Eugene Antony Whang**, San Francisco, CA (US)

(73) Assignee: **Apple Inc.**, Cupertino, CA (US)

(*) Notice: This patent is subject to a terminal disclaimer.

(**) Term: **15 Years**

(21) Appl. No.: **29/959,468**

(22) Filed: **Aug. 26, 2024**

Related U.S. Application Data

(63) Continuation of application No. 29/878,550, filed on Jun. 23, 2023, now Pat. No. Des. 1,040,131, which is

a continuation of application No. 29/856,905, filed on Oct. 18, 2022, now Pat. No. Des. 994,635, which is a continuation of application No. 29/848,299, filed on Aug. 1, 2022, now Pat. No. Des. 973,630, which is a continuation of application No. 29/801,991, filed on Aug. 2, 2021, now Pat. No. Des. 959,406, which is a continuation of application No. 29/731,847, filed on Apr. 17, 2020, now Pat. No. Des. 926,725.

CLAIM

The ornamental design for headphones as shown and described.

DESCRIPTION

FIG. 1 is a top front perspective view of headphones showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the headphones that form no part of the claimed design.

1 Claim, 7 Drawing Sheets

FIG. 1

FIG. 2

FIG. 3

FIG. 4

FIG. 5

FIG. 6

FIG. 7

FIG. 8
